WALTER JOY, OF SOMERVILLE, MASSACHUSETTS, ASSIGNOR TO CAMBRIDGE RUBBER CO.,
OF CAMBRIDGE, MASSACHUSETTS, A CORPORATION OF MASSACHUSETTS

OVERSHOE AND METHOD OF MAKING SAME

Application filed October 18, 1929. Serial No. 400,574.

This invention relates to the manufacture of rubber footwear and will be herein disclosed as embodied in an overshoe of a common type.

5 In a considerable variety of rubber shoes it is usual to provide a flap at the front of the shoe to cover the front slit or opening. In making such shoes the flap usually is adhesively secured to the upper at one side of the front slit, and a stay strip or flap wing is applied to the upper at the opposite side of the slit, these parts being permanently secured in position by their union with the upper during vulcanization. Both the flap 10 wings are punched for fasteners prior to being attached to the shoe, but the fasteners usually are not set until after the vulcanizing operation has been performed. It is a common occurrence to find that the fasteners do not line up properly in the finished shoe, either due to uneven warping of the parts or the failure to register the flap wings properly with each other in applying them to the shoe. The present invention is especially 15 concerned with these factors and it aims to improve both the construction and methods of making shoes of this type with a view to simplifying the manufacturing operations and improving the finished product.

20 In shoes of this type it is a very common experience to have the vamp tear at the lower end of the slit or "throat" portion of the shoe. It is, therefore, a further object of the invention to devise a simple and entirely practical method of reinforcing the shoe at this point and preventing damage from this cause.

The nature of the invention will be readily understood from the following description when read in connection with the accompanying drawings, and the novel features will be particularly pointed out in the appended claims.

25 In the drawings,

Figure 1 is a plan view of a flap construction embodying features of this invention;

Fig. 2 is a plan view of the flap shown in Fig. 1 when folded preparatory to being applied to a shoe;

Fig. 3 is a perspective view of a typical shoe at the time the flap is applied to it;

Fig. 4 is a similar view showing the flap after being applied;

Fig. 5 is a sectional view through the flap and upper of the finished shoe;

Fig. 6 is a perspective view of the shoe in substantially the form in which it is vulcanized;

Fig. 7 is a horizontal sectional view through the flap and adjacent parts of the shoe shown in Fig. 6; and

Fig. 8 is a perspective view of the finished shoe.

Referring first to Figs. 3 and 4, it will be observed that the overshoe there shown is of a common type, and includes an upper 2, a rubber sole 3, heel 4, and the usual foxings 5 and 6. It is a common practice to cut the upper for a shoe of this type from a composite fabric consisting of an outer wearing ply, which may be of either rubber or fabric, united throughout its area to an inner lining 70 ply of fabric. In some cases the upper consists of a vamp and quarters united by adhesives or by stitching, while in other cases, as in the construction shown, the vamp and quarters are integral or in a single piece, and their edges are united at the back seam 7.

In making a shoe of this type, the various parts are assembled on the last, the different parts of the shoe being adhesively secured to each other. The particular shoe shown in Fig. 3 is provided with a cuff 8, and an ornamental strip 9 extends across 85 the vamp portion of the shoe. When the shoe is at about this stage of the process the flap usually is applied to the upper.

Referring to Figs. 1 and 2, which show a typical flap construction of one form embodying this invention, it will be seen that the flap comprises two sections or wings indicated at 12 and 14, respectively. The individual members of cooperating pairs of fasteners are secured to the respective wings. 90 In this particular instance the fasteners are of the snap type and comprise studs 15 set into the wing or flap section 14 and socket members 16 set into the opposite wing 12. The wing 14 is to be laid flat against the upper 2 95 100

and vulcanized thereto so that it will, in effect, form a part of the upper in the finished shoe, while the wing 12 is to be secured to the upper only at its margin so that it can 5 swing into an open or closed position.

These wings may be made of the same or different materials. Usually the wing 12 has an inner or lining ply of strong but inexpensive fabric and an outer ply of rubber 10 or fabric of a color contrasting with that of the upper 2. Often the outer ply is made of an ornamental fabric and usually is of the same material as that of the cuff 8. The wing 14 usually consists of an outer ply of fabric 15 like the lining of the wing 12, and an inner ply of rubber or rubberized fabric so that it will form a firm union with the upper material 2. The two wings are very slightly overlapped, one upon the other, and adhesively 20 secured together at their lower edges, as indicated at 17, Figs. 1 and 2, and the margin 16' also is rubberized or coated with rubber cement. If the upper 2 has an outer 25 ply of fabric it may be coated with rubber cement at the points where the wings are to be applied to it.

A short length of flexible cord 18, which preferably has been previously impregnated with rubber, rubber latex or the like, is next 30 placed across the lower margins of the wings where it will connect them. Preferably, although not necessarily, this cord is made of cotton, flax or some other relatively strong fibre, and the part so applied to the flap is 35 bent into a V-shape, one leg being adhesively attached to the margin 16' and the other to the lower margin of the rubberized surface of the wing 14. The adjacent edges of these wings at this time are separated by a narrow 40 slit 19.

The flap now is folded along approximately the dotted line 20, Fig. 1, the wing 12, Fig. 1, being carried away from the observer and folded over upon the wing 14 and the 45 sockets 16 snapped on their respective studs 15.

In this condition the flap is applied to the shoe. At this time the front of the upper is closed, as shown in Fig. 3, and the inner 50 rubberized surface of the wing 14 and the margin 16' of the wing 12 are simply pressed firmly against the instep portion of the upper with the line of fold 20 extending up said portion and located approximately centrally 55 of this part of the shoe. The rubberized surfaces readily adhere to each other and thus securely hold the wing 14 and the margin 16' in their proper positions on the shoe, the fasteners holding the wing 12 in its closed 60 position.

A finish strip 21 of rubber, Figs. 6 and 7, usually is applied before the shoe is vulcanized to cover the joint between the flap and the vamp and to give the front of the 65 shoe a neater and more finished appearance.

The "making" operations are completed while the shoe is on the last, and the shoe is subsequently finished in a manner which depends upon the nature of the shoe, the requirements of the trade and the preference of the 70 different manufacturers. These finishing operations may be regarded as including the vulcanizing of the shoe, which is performed while the shoe remains on the last or form on which it was built. After the vulcanizing 75 operation, the wing 12 of the flap is unsnapped and the workman then forms the front slit in the upper of the shoe by cutting through the material of the upper, against the last, starting at the lower end of the slit 80 19, just above the cord 18, and cutting through to the top of the shoe. This completes the manufacture of the shoe so far as structure is concerned.

It will be observed that in this process the flap is completed before it is applied to the shoe. The two wings of the flap are folded one upon the other and brought into substantially their final relationship before they are punched to receive the studs or sockets or other fastener members used, and they may thereafter be folded and snapped together and kept in this relationship as they go through additional steps of the manufacturing process. As above stated, they are kept in their closed relationship during the vulcanizing operation. This avoids any difficulty in registering the fasteners properly with each other; it permits the setting of the fasteners before the flap is attached to the shoe and at a time when this operation can be performed more rapidly than according to prior practice, and it avoids any possibility of the two wings of the flap warping one 90 with reference to the other which has been an especially troublesome factor heretofore.

It will also be understood that when the shoe is finished, the cord 18 is embedded in the material of the upper between the flap and the outer ply 2 of the upper material, 100 and that the vulcanizing operation securely unites the rubber in the cord with that in the flap and upper. The cord 18, being relatively strong and securely embedded in and vulcanized to adjacent parts of the shoe, effectually prevents the tearing of the shoe at the lower end of the slit which often is caused by pulling the flap open violently when taking the shoe off, or by excessive strain in putting the shoe on. The cord extends directly across the throat closely adjacent to the lower end of the slit, ample lengths of cord being embedded in the shoe to anchor it securely in place. The particular location of the legs of the cord make it inconspicuous 110 in the finished shoe.

A further advantage of this shoe construction is that it avoids the objectionable bunch at the throat of the shoe which has been common in prior constructions, due to the over- 120

lapping of substantial portions of the flap at this point. The assembling operations also are facilitated. It has been definitely determined in practice that the percentage 5 of "seconds" or unsaleable shoes is very substantially reduced by this invention.

While I have herein shown and described a preferred embodiment of my invention, it will be understood that the invention may 10 be embodied in other forms and that minor departures in the process may be made without departing from the spirit or scope of the invention.

Having thus described my invention, what 15 I desire to claim as new is:

1. That improvement in methods of making rubber shoes which consists in assembling parts of a shoe including an upper providing a front slit in said upper, at some 20 stage of the process applying a flexible cord containing rubber to the upper across the lower end of said slit with portions of said cord extending backwardly at opposite sides of said slit, and causing the rubber in said 25 cord to unite with the rubber in the adjacent parts of the shoe to secure the cord permanently in said position in the shoe.

2. That improvement in methods of making rubber shoes which consists in assembling 30 parts of a shoe including an upper, providing a front slit in said upper, at some stage of the process applying a cord containing rubber to the shoe across the lower end of said slit with portions of said cord extending backwardly at opposite sides of said slit, and vulcanizing the shoe with said cord so embedded and thereby permanently securing the 35 cord in said position in the shoe.

3. That improvement in methods of making 40 rubber shoes which consists in assembling parts of a shoe including an upper, providing a flap having two wings equipped with cooperating fastening members for holding the flap closed, adhesively securing said flap 45 to the upper of the shoe at the front thereof, placing a flexible cord across the junction of said wings where it will reinforce the throat of the shoe, and vulcanizing the shoe while utilizing said fastening members to hold the 50 flap in its closed condition.

4. That improvement in methods of making 55 rubber shoes which consists in assembling parts of a shoe on a last, said parts including an upper closed at the front, providing a fold- 60 ed flap having two wings partly separated by a slit and equipped with cooperating fastener members located, respectively, on said wings, adhesively securing said flap to the instep portion of said shoe, vulcanizing the shoe 65 with said fastener members holding said wings closed during the vulcanizing operation, and thereafter cutting through the upper along the slit between said wings to form the front slit in the shoe.

5. That improvement in methods of mak-

ing rubber shoes which consists in assembling parts of a shoe on a last, said parts including an upper closed at the front, providing a slitted flap having two wings, equipping 70 said wings with cooperating fastener members to hold the flap closed, attaching a flexible cord to the lower portion of said wings where it will extend across the slit in the flap, folding said flap, adhesively securing said 75 flap in its folded and closed condition to the shoe with the fold extending up the front of the shoe and said cord lying between the flap and the upper, vulcanizing the shoe, and thereafter opening the flap and slitting the upper of the shoe along the slit in said flap 80 to form the instep slit or opening in the shoe.

6. A vulcanized rubber shoe having a slit along the front thereof to permit the shoe to be opened, a flap for closing said slit, and a rubberized, fibrous reinforcing cord embedded and vulcanized in said shoe across the throat portion thereof at the lower end of said slit, said cord being bent into a V-shape and having a leg extending along the margin of the flap adjacent to the throat, and 90 another leg extending along the opposite side of the throat to strengthen the shoe against ripping when the flap is opened.

7. That improvement in methods of making rubber shoes which consists in assembling 95 parts of a shoe on a last, said parts including an upper closed at the front, providing a folded flap having two wings equipped with cooperating fastener members located, respectively, on said wings, adhesively securing said flap to the instep portion of a shoe, vulcanizing the shoe, utilizing said fastener members to hold said wings closed during the vulcanizing operation, and thereafter 100 opening said flap and cutting through the upper from a point near the lower end of the flap to the top of the upper to form the front slit in the shoe.

8. A vulcanized rubber shoe having a slit 110 along the front thereof to permit the shoe to be opened, a flap for closing said slit, and a rubberized, fibrous cord extending across the lower end of said slit and backwardly at opposite sides of the slit, said cord being embedded and vulcanized in the portions of said 115 shoe at opposite sides of the slit to reinforce the shoe against ripping when the flap is opened.
